UNITED STATES PATENT OFFICE.

HENRY W. SCHWIMMER, OF INDIANAPOLIS, INDIANA, ASSIGNOR TO LOUIS MAR-MOREK AND HARRY KOIN.

CORN-POPPING MACHINE.

Application filed September 29, 1923. Serial No. 665,629.

To all whom it may concern:

Be it known that I, HENRY W. SCHWIMMER, a citizen of the United States, residing at Indianapolis, in the county of Marion and State of Indiana, have invented a new and useful Corn-Popping Machine, of which the following is a specification, reference being had to the accompanying drawings and to the letters and figures of reference 10 marked thereon.

This invention relates to a machine of the type that is designed to operate continuously and in an interesting and entertaining manner, so that the operations may be attractive to observers who may purchase freshly popped corn, the invention having reference more particularly to a machine whereby corn may be automatically popped and buttered and also kept warm while 20 being sold.

An object of the invention is to provide a corn-popping machine of the above-mentioned character which may be built compactly and at small cost, so as to be available to those who retail in small quantities, 25 but which may be built also in larger sizes when desired.

Another object is to provide a corn-popping machine of such construction as to permit of the maximum space for popped corn in a small show-case, in order to supply the 30 needs of merchants who may have limited space in a store for a corn-popping machine.

A further object is to provide an automatic corn-popping machine which shall be of such construction as to operate and perform its functions in a cleanly and sanitary manner.

A still further object is to provide an improved corn-popping machine of such construction as to convert all the corn into palatable and wholesome food, particularly to roast or parch unpopped corn usually present when carrying out popping operations, such unpopped or "shot" corn when properly parched being desired by many in preference to popped corn.

With the above-mentioned and other objects in view, the invention consists in an 50 improved electrically heated and driven and

automatically fed machine, so constructed as to be well adapted not only for popping corn but for parching such corn as is usually found to be incapable of being popped, the machine including automatic buttering apparatus; and the invention consists also further in the novel parts and in the combinations and arrangements of parts in a corn-popping machine as hereinafter particularly described and further defined in the claims 60 appended hereto.

Referring to the drawings,—Figure 1 is a perspective view of a corn-popping machine constructed substantially in accordance with the invention, in connection with 65 a glass show case for the product of the machine; Fig. 2 is a fragmentary top plan showing portions of the machine on an enlarged scale; Fig. 3 is a vertical central section of the machine proper, portions of 70 the case being broken away; Fig. 4 is a fragmentary sectional elevation similar to the preceding figure but with parts of the machine in relatively different positions; Fig. 5 is a fragmentary transverse section 75 of an improved feeder illustrating the manner of feeding corn to the popping apparatus; Fig. 6 is a fragmentary transverse section of the feeder illustrating that part thereof whereby butter may be fed to the 80 popping apparatus; Fig. 7 is a fragmentary sectional detail more clearly showing parts of the structure on an enlarged scale; and, Fig. 8 is a fragmentary sectional detail 85 clearly showing parts of the controlling mechanism of the machine on an enlarged scale.

Similar reference characters in the various figures of the drawings indicate corresponding elements or features of construction herein referred to in detail.

In practically carrying out the objects of the invention a suitable machinery frame is provided which preferably comprises a show case having transparent sides supported in a suitable frame 1 which has a floor 2 and a roof or top 3. The apparatus comprises a slender hollow metallic post 4 which is firmly secured to the middle portion of the floor 2 and extends upward a suitable dis- 100

tance to permit the accumulation of popped corn on the floor, and a metallic bowl 5 is fixed at the center of its bottom to the upper portion of the post and has an internal annular ledge 6 below the top of the bowl, the ledge supporting an electric heater unit 7 which is of proper height to permit a wall portion 8 of the bowl to extend higher than the unit. An electric circuit wire cable 9 is extended into the lower portion of the frame and up through the post to the heater unit. An improved shallow pan 10 on which to pop the corn is provided and preferably is composed of sheet metal and dished so that the top surface is concave, the middle portion of the pan being pressed up or molded to form a central hollow boss 11. The pan preferably has a marginal portion pressed up, spun or molded to constitute an annular rib 12 designed to nest into the upper wall portion 8, the metal forming the rib extending over to constitute an annular seat member 13 that rests upon the top of the wall portion 8 and has a rim portion 14 extending therefrom downwardly a sufficient distance to cover the groove formed by striking up the ledge 6, the lower edge of the rim having a bead 15 thereon. The dimensions are such that the lower portion 30 of the pan is slightly above the heater unit to permit free but slight downward movement resulting from expansion of the pan when heated, and permitting heat to be distributed under the pan so that the outer 35 portions shall become heated to approximately the same degree as the middle portion of the pan.

A novel cover for the popper pan is provided which comprises a top portion 16 and a circular side portion 17, the latter being of proper diameter to slip freely over the rim portion 14 of the pan to constitute a pan side wall, and having a bead 18 on its lower edge to rest upon the bead 15. The 40 top portion 16 has a central annular head 19 provided with internal screw threads 20, the head having a cross-bar or crosshead member 21 fixed thereon that has an opening therein corresponding to the opening 45 in the head. The boss 11 has a swivel device 50 preferably composed of two parts 22 and 23 secured together by a screw 24 and rotatably arranged centrally in the boss. An agitator is provided which comprises a hub 55 and a clutch member 26 secured together and rotatable on the swivel device, and fingers 27 radially arranged on the hub and adapted to slide on the top of the pan, each finger extending from the hub upwardly 60 across the inclined portion of the pan approximately to the rib 12. A driving shaft 28 is vertically arranged and extends loosely through the head 19 and has a clutch member 29 secured to its lower portion, the end 65 of the shaft being centered in the top of

the swivel device, the clutch member 29 having lugs 30 entering suitable sockets in the member 26 whereby to rotate the agitator. The upper portion of the shaft 28, the shaft extending through the roof 3, is suitably supported rotatably, as by means of a stand 31 in which the shaft is journaled, and the shaft is driven by suitable means, preferably a bevel gear wheel 32 secured to the shaft above the stand. The shaft is provided with screw threads to operate in connection with the threads 20, and preferably a sleeve 33 is adjustably arranged on the shaft and is provided with external screw threads 34, the sleeve being secured to the shaft by means of a set screw 35, to permit the cover to be moved upward a short distance before the screw threads 20 are carried into engagement with the threads 34, the adjustability of the sleeve 33 being provided for variation of the free travel of the cover. Preferably the cross-bar 21 has arms 36 secured thereto that are integrally connected to a guide member 37 arranged to slide along the shaft 28, to constitute a centering guide yoke for the cover, particularly to prevent tilting of the cover in operation.

Various means may be provided for driving the shaft 28, a suitable mechanism preferably being a pair of standards 38 and 39 secured upon the top of the roof 3, a shaft 40 rotatably supported by the standards and having a large pulley 41 secured thereto, an electric motor 42 secured upon the roof and provided with a small driving pulley 43, a belt 44 connected with the pulleys, a sleeve 45 arranged to slide on the shaft 40 and suitably rotated by the shaft, as by means of a pin or spline 46 secured to the shaft and extending into a longitudinal slot 47 in the sleeve, and two bevel pinions 48 and 49 reversely fixed on the sleeve to be alternately carried into contact with the gear wheel 32. The sleeve 47 is moved and controlled preferably by means of a collar 50 arranged thereon to permit rotation of the sleeve and having a jaw 51 thereon. A pivot stand 52 is secured on the top of the roof 3 and has a pivot 53 thereon which supports a shifter lever 54 that has a short arm 55 properly connected with the jaw 51 whereby to slide the sleeve 45. A controlling rod 56 is vertically arranged so as to extend through the roof and is connected to the lever 54, and a collar 57 is adjustably secured to the rod above the cross-bar 21, the latter having a suitable opening through which the rod extends, the rod extending through the top of the cover and having a collar 58 adjustably secured thereto under the top portion 16 of the cover. This arrangement enables the cover to control the direction of motions of the driving shaft 28. In order to insure the reverse move- 125 130

ments, the shifter is provided with a "kicker" comprising a hollow cylinder 59 fixed on the stand 52 and having a plunger 60 vertically guided therein and forcibly projected upward by means of a coil spring 61 arranged in the cylinder beneath the plunger, the plunger having a pointed or wedge-like upper portion 62 that engages a similar projection 63 reversely arranged and fixed 10 on the shifter arm below its pivot 53, the plunger acting wedge-like to quickly move the shifter after having been slowly moved by the cover, for completing the shifting of gears in a well known manner. Briefly, the 15 popper pan cover moves slowly and moves the shifter until one pinion on the sleeve 45 is nearly disconnected from the gear wheel 32, the finger 63 having forced down the plunger 60 and passed over the top of the 20 plunger, the plunger being immediately forced up against the opposite side of the finger and causing further movement of the shifter, so as to quickly disengage the pinion and cause the opposite pinion to move 25 into contact with the gear wheel 32 and reversely rotate the shaft 28.

A novel feeder is provided which comprises a cylindrical casing 64 having suitable end members 65 and 66 fixed thereto that are provided with journal bearings 67 and 68 respectively, the casing being secured horizontally on the top of the roof 3, and the upper and lower portions of the casing are adapted to constitute valve seats, 35 the upper portion having a valve port 69 therein. A reservoir 70 having a hopper bottom is supported upon the feeder casing and has a discharge aperture 71 in its bottom to direct corn into the port 69. The 40 reservoir preferably has an internal ledge 72 on which a suitable cover 73 is removably supported. The lower portion of the casing has a valve port 74 therein adjacent to one end of the casing and also a smaller 45 port 75 adjacent to the opposite end of the casing. A feed-pipe 76 is connected with the port 74 and extends down through the roof 3 and through a suitable opening in the top portion 16 of the cover, the cross-bar 21 preferably having a suitable opening 50 through which the feed-pipe extends, to prevent rotation of the cover. Another feed-pipe 77 is connected with the port 75 and extends also through the top of the 55 cover to feed butter to the popper pan. A hollow cylinder 78 adapted to constitute a valve is rotatively arranged in the valve casing and has ends 79 and 80 provided with journals 81 and 82 rotatively supported in the bearings 67 and 68 respectively. One portion of the cylinder 78 has a discharge port 83 through which to discharge corn into the port 74, and another portion has a discharge port 84 to discharge melted butter or grease into the port 75. Another por-

tion of the cylinder 78 has a port 85 therein to receive corn from the port 69. The valve cylinder has a partition 86 therein in proximity to the end 80 to form a reservoir for the butter separate from the compartment 70 for corn in the feeder valve. Preferably the compartment for corn has an inclined plate 87 therein extending from the partition downwardly at an inclination to the lower portion of the cylinder 78 adjacent to 75 the port 83 to constitute a hopper bottom. The end 80 is provided with a filling neck 88 through which to supply the proper chamber with butter or grease. The end or head 79 has a lug pin 89 fixed on the outer 80 side thereof to operate and control the feeder valve, and a rod 90 is adjustably secured to the cross-bar 21 and extends upward through the roof 3 by which it is guided and has a finger 91 on one side thereof to engage the pin and pull downward thereon to rotate the feeder valve in one direction, and the rod has also a shorter finger 92 below the other finger to engage and push upward on the pin to rotate the 90 feeder valve in the opposite direction a suitable distance and then pass onward to permit the cover to move upward indefinitely without moving the valve, which may be occasioned by tardy reversing of the driving shaft 28.

In practical use, a charge of corn is placed upon the popper pan, the pan having previously been greased with suitable substance and the electric current switched into the heater. The motor 42 is started and the operations begin. Or, without charging the popper pan with corn the pan is first permitted to become heated and then the machine is started. In case the cover is not down upon the popper pan but is being moved downward by the screw on the driving shaft, as the cover head 19 leaves the screw the cover falls by the force of gravity to its normal position so as to cover the pan. The cover in its descent engages the collar 58 and pulls down the rod 56 so that the gearing is properly set to drive the shaft 28 in one direction, and the shaft turns the agitator. During the descent of the cover the feeder valve carries the port 84 to the port 75 to discharge a small quantity of butter or grease which flows onto the popper pan, and the further movement of the cover pulls down the rod 90 fully so that the lug finger 91 further rotates the valve which brings the port 83 to the port 74 to discharge corn through the feed-pipe 76 onto the pan, the corn being stirred and agitated on the pan by the moving agitator fingers 27, the feeder valve having closed the port 69 against flow of corn from the reservoir, the charging positions being illustrated in Fig. 3. The popping pan having been heated, 13 the corn is heated thereby and pops and ex-

pands until all that can be popped becomes popped and the gradually increasing volume due to expansion of the corn forces up the cover until some of the popped corn may be forced from under the lower edge of the cover by the action of the agitator which tends to move the lighter popped corn out over the rib of the pan. As the cover rises the screw threads 20 come into engagement 10 with the screw threads 34, after which the cover is slowly forced upward by screw power. Previously to the engagement of the screws, the rod 90 is idly moved upward until the finger 92 comes into contact with 15 the pin 89 immediately after engagement of the screws, and likewise the cross-bar 21 and the cover move upward without shifting the rod 56, the cross-bar engaging the collar 57 immediately after the screws are 20 in engagement, so that the rod 56 is subsequently forced upward, and the finger 92 in contact with the pin 89 causes rotation of the feeder valve which during its movement carries the port 84 across the port 75 so as 25 to discharge a small quantity of butter onto the pan, which previously has been cleared of the parched corn remaining in the pan after discharge of the popped corn, the un- 30 popped corn being temporarily retained in the pan by the force of gravity because of its relatively heavy weight until parched. A further upward movement of the cover approximately to the position indicated in Figs. 1 and 4 causes the maximum movement 35 of the feeder valve so that the port 74 has become closed, and the port 85 is brought to the port 89 and admits a charge of corn from the reservoir into the feeder valve ready for the following period in the cycle 40 of operations resulting from the shifting of the gearing, so that the shaft 28 is rotated in the opposite direction to cause the lowering of the cover by screw power that enables the cover to again operate the feeder valve in the opposite direction, the operations being continued automatically in the manner above-described. The popped and 45 parched corn falls onto the floor 2 and becomes piled about the slender post 4, being 50 kept warm by heat from the bowl and the port and the popped corn may be readily separated on the floor from the heavier parched corn and dispensed as may be desired.

55 What is claimed as new is:—

1. A corn-popping machine having a stationary concave pan, a heater arranged below the pan, a rotary shaft guided above the pan, a pan cover movably guided on the shaft, and a hub secured to the shaft and having agitator fingers thereon extending from the lower portion upwardly across the surface of the pan.

60 2. A corn-popping machine including a stationary pan, a cover removably arranged

upon the pan to be raised by action of corn popping and expanding upon the pan, the cover having a side portion slipping over the edge of the pan, an agitator arranged upon the pan, and means for rotating the 70 agitator and automatically lifting the cover away from the pan when raised.

3. A corn-popping machine including a stationary concave pan, a heater below the pan, a cover removably arranged upon the 75 pan to be lifted bodily therefrom by action of a quantity of corn popping and expanding upon the pan, the cover having a side portion slipping over the edge of the pan, an agitator arranged upon the pan, and a 80 rotary shaft extending loosely through the cover and secured to the agitator.

4. A corn-popping machine having a stationary concave pan and a heater, a rotary shaft guided above the pan, a hub secured 85 to the shaft and having radial agitator fingers extending across the pan, a cover for the pan loosely guided on the shaft to be bodily lifted by action of expansion of the corn being popped upon the pan, and means enabling the shaft to alternately raise 90 and lower the cover.

5. A corn-popping machine having a stationary concave pan, the edge portion of the pan being provided with an upwardly-extending relatively low annular rib, a heater stationarily arranged below the pan, a shaft rotatably guided above the pan, a pan cover movably guided on the shaft, and a hub secured to the shaft and having agitator 95 fingers thereon extending gradually upwardly across the surface of the pan approximately to the rib.

6. A corn-popping machine including a pan, a heater below the pan, a cover removably arranged upon the pan to be lifted therefrom by corn popping and expanding upon the pan, an agitator upon the pan, a shaft extending rotatably through the cover and secured to the agitator, and means controlled by the shaft and co-operating therewith to further lift the cover away from the pan.

7. A corn-popping machine including a pan, a heater arranged below the pan, a 115 shaft guided above the pan, agitator fingers having connection with the shaft, a cover for the pan loosely guided on the shaft for vertical movement, a feeder operatively arranged above the cover and having an actuating device, a feed-pipe connected with the feeder and extending through the cover, and an operating-rod operatively connected with the cover and adapted to controllably operate the actuating device of the feeder.

8. A corn-popping machine including a bowl, a pan arranged in the bowl and having an upturned rib on its edge, the rib extending over the upper edge of the bowl and being supported thereon, a shaft guided 120

above the pan, a hub secured to the shaft and having radial agitator fingers extending across the pan to the rib, a heater arranged in the bowl below the pan, and a 5 cover comprising a top loosely guided on the shaft and a rim to extend loosely about said rib to be lifted by expanding popping corn upon the pan.

9. A corn-popping machine including a 10 hollow post, a bowl secured to the top of the post and having a ledge on the inner side thereof, an electrical heater unit supported on the ledge, circuit wires for the unit arranged in the post, a popper pan 15 bodily supported upon the top of the bowl, a cover removably seated on the pan, means for lifting the cover from the pan a feeder arranged higher than the cover and having a feed-pipe connected thereto that extends 20 through the top of the cover, and means for operating and controlling the feeder having connection with the cover.

10. A corn-popping machine including a 25 floor, a post secured upon the floor and having a bowl thereon, a heater arranged in the bowl, a pan bodily supported upon the top of the bowl, a cover removably arranged upon the bowl to cover the pan, an agitator movable upon the pan, a shaft rotatable 30 vertically upon the pan and secured to the agitator, means for reversibly rotating the shaft having controlling means operated by the cover, and means for feeding corn and 35 butter to the pan through the cover and provided with operating means having connection with the cover.

11. A corn-popping machine including a 40 stationary pan, a heater arranged below the pan, a shaft rotatably arranged vertically above the pan and having screw threads thereon above the pan, the lower end of the shaft being guided by the pan, agitator fingers actuated by the shaft upon the pan, a 45 cover for the pan loosely guided thereon and having a screw-threaded head to engage the screw threads on the shaft, reversible driving gearing connected with the shaft, and controlling means actuated by means of the cover and controlling the gearing to intermittently reverse the direction of motion of the shaft.

12. A corn-popping machine including a 50 stationary pan, a heater arranged below the pan, a shaft rotatably arranged vertically above the pan and partially guided thereby, a movable cover for the pan loosely guided vertically by the shaft and the pan, the cover having a crosshead fixed thereon, agitator fingers carried by the shaft over the pan, a feeder operatively arranged above the cover and having an actuating device, a feed-pipe connected with the feeder and extending through the cover and its crosshead, and an operating-rod secured to the crosshead and having means co-operating with

the actuating device to controllably operate the feeder.

13. A corn-popping machine including a 55 pan, a shaft rotatably guided vertically on the pan and having screw-threads thereon, a 70 cover removably arranged on the pan and having a screw-threaded head to engage the threads on the shaft for raising or lowering the cover, an agitator operated by the shaft upon the pan, means for reversibly rotating the shaft provided with controlling apparatus operated by means of the cover, a dual feeder arranged above the cover and having feed-pipes extending through the cover, the 75 feeder being provided with an actuating device, and an operating rod operated by the cover and having lugs to alternately engage and operate the actuating device.

14. A corn-popping machine including a 80 popper pan, a cover removably arranged on the pan and having a threaded head, a rotatable vertical shaft having threads to engage the threaded head for lifting or lowering the cover, the shaft being rotatably connected with the popper pan, an agitator on the pan secured to the shaft, a feeder arranged higher than the cover and comprising a horizontal cylindrical case having an inlet port in its upper portion and two separate discharge ports in its lower portion, 85 two feed-pipes connected with the discharge ports respectively and extending through the cover, a hollow cylindrical valve rotatively guided in the case and having an inlet port and two outlet ports, the valve having a partition therein between the outlet ports, a hopper on the top of the case to discharge 90 into the inlet ports, and means to operate the valve having connection with the cover.

15. In a corn-popping machine, the combination of a stationary bowl, a popper pan supported in the bowl, an electrical heater unit supported in the bowl below the pan, a rotary shaft guided above the pan and having an agitator connected thereto to be rotated upon the pan, a cover loosely guided on the shaft and the bowl, and means actuated by the shaft to lift or to lower the cover.

16. In a corn-popping machine, the combination, with a heater, a popper pan, an agitator rotatable on the pan, and a cover removably arranged to cover the agitator and the pan, of reversible screw-power means to operate in connection with the cover to raise or lower the cover, said means including a rotatable shaft extending through the cover and secured to the agitator.

17. In a corn-popping machine, the combination, with a heater, and a support therefor, of a popper pan having a concave top surface, the marginal portion of the pan having an annular rib thereon extending about the higher portion of said surface, the 115 rib extending over and resting upon said 120

support, an agitator rotatably arranged upon said surface, a cover removably arranged on the pan to cover said surface and the agitator, and a rotatable shaft extending through the cover and secured to the agitator.

18. In a corn-popping machine, the combination, with a popper pan and an agitator thereon, of a cover for the pan removably arranged thereon, a feeder casing having discharge ports in the lower portion thereof, feed-pipes connected with the ports respectively and extending loosely through the top of said cover, a hollow valve rotatively arranged in the casing and having two chambers provided respectively with outlet ports to feed to the discharge port respectively, a reservoir supported upon said casing to feed to the valve, and means having connection with said cover to engage and operate said valve.

19. In a corn-popping machine, the combination, with a feeder having an operating part, of a popper pan arranged lower than the feeder, a cover removably arranged upon the pan and having a cross-bar fixed thereto, the cover being provided with screw threads, a shaft rotatably guided upon the popper pan and extending through the top of the cover, the shaft having a screw thereon to engage said screw threads, means to reversibly rotate the shaft, a feed-pipe connected with the feeder and extending loosely through the top of the cover and also loosely through the cross-bar, and a rod secured to the cross-bar and provided with means to engage and operate the operating part of the feeder.

20. In a corn-popping machine, the combination, with a popper pan and a heater beneath the pan, of an agitator rotatably arranged on the pan, a cover removably arranged to cover the agitator and the pan, a rotatable shaft extending loosely through the cover and secured to the agitator, a feeder arranged higher than the cover and comprising a valve case and a hollow valve rotatively arranged therein, the valve having a lug pin fixed thereon, a feed-pipe connected with the valve case and extending loosely through the top of the cover, and a rod having connection with the valve and extending upward and in proximity to the lug pin, the rod having two fingers thereon to alternately engage the pin to operate the valve.

21. In a corn-popping machine, the combination, with a bowl and a heater supported in the bowl at a distance below the top thereof, of a dished popper pan having a central boss, the top of the pan being concave and the pan having a marginal upturned rib that extends over upon the top of the bowl and thereby supports the pan above the heater, the rib having a rim thereon extend-

ing downward and about the bowl and provided with a bead, an agitator rotatable on the popper pan, a cover comprising a top and a rim, the rim extending removably over the rim on the rib and being supported upon said bead, a rotatable shaft guided on said boss and extending through the top of the cover, and clutch devices connecting the agitator to the shaft.

22. In a corn-popping machine, the combination, with a floor and a roof, of a bowl having a supporting post secured upon the floor, a heater arranged in the bowl, a popper pan in the bowl supported upon the top of the bowl, an agitator upon the pan, a cover removably arranged on the pan and having a hollow head provided therein with screw threads, a cross-bar secured to said head, a vertical shaft secured to the agitator and extending through said head and said roof and having a screw to engage said threads for raising or lowering the cover, the shaft being rotatably supported upon said roof and having a bevel gear wheel secured to the top thereof, a shaft rotatably supported horizontally upon said roof, a sleeve shiftably arranged on the horizontal shaft and having two bevel pinions thereon to be moved alternately to the gear wheel, means enabling the horizontal shaft to rotate the sleeve, a shifter having connection with the sleeve and co-operating with said roof to shift the sleeve, the shifter being provided with an operating-rod extending through said roof and also through said cross-bar and through the top of said cover, a collar secured to said rod above said cross-bar, and a collar secured to said rod below the top of said cover.

23. In a corn-popping machine, the combination of a stationary bowl, a flat heater supported in the bowl by the wall thereof, a dished popper pan supported in the bowl above the heater, a shaft rotatably guided above the pan, a movable cover for the pan loosely guided vertically by the shaft and the pan and provided with screw threads in the top thereof, a sleeve adjustably secured to the shaft and having screw threads thereon to operate in connection with the threads in the cover, and an agitator actuated by the shaft.

24. In a corn-popping machine, the combination of a metallic bowl provided on the center of its bottom with a tall and slender supporting post, the base portion of the post being rigidly supported, a heater arranged in the bowl, a popper pan having support on the bowl, a cover having a rim portion removably guided on the bowl, a rotatable shaft extending through the cover, and an agitator arranged upon the popper pan and connected to the shaft.

25. In a corn-popping machine, the combination of a metallic bowl, a popper pan

supported in the bowl, an electrical heater supported in the bowl below the pan, an agitator arranged to operate upon the pan, a cover having a rim portion loosely guided on the bowl to be lifted therefrom by means of corn being popped upon the pan, a rotary shaft extending loosely through the cover and connected to the agitator, and a tall and slender post rigidly connected to the central portion of the bowl bottom to solely support the bowl in an elevated position.

In testimony whereof, I affix my signature on the 26th day of September, 1923.

HENRY W. SCHWIMMER.
